MINIATURE DECORATIVE TREE

William Christiansen, Jr., Palmetto, Fla., assignor to
Snow Foam Products, Inc., El Monte, Calif.

Filed Sept. 21, 1972, Ser. No. 292,481

Term of patent 14 years

Int. Cl. D11—02
U.S. Cl. D29—1 A

Fig. 1.

Fig. 2.

Fig. 3.

Fig. 4.

Fig. 5.

Fig. 6.

FIG. 1 is a bottom plan view of a miniature decorative tree showing my new design in nested condition;

FIG. 2 is a side elevational view thereof, all sides being the same;

FIG. 3 is a top plan view thereof;

FIG. 4 is a top plan view of the assembled tree;

FIG. 5 is a side elevational view of the assembled tree; and

FIG. 6 is a bottom plan view of the assembled tree.

I claim:

The ornamental design for a miniature decorative tree, substantially as shown and described.
